UNITED STATES PATENT OFFICE.

WILLIAM F. KELLER, OF DETROIT, MICHIGAN.

DESIGN FOR A TOY MONKEY.

59,011.

Specification for Design. Patented Sept. 13, 1921.

Application filed April 11, 1921. Serial No. 460,486. Term of patent 14 years.

To all whom it may concern:

Be it known that I, **WILLIAM F. KELLER**, a citizen of the United States of America, residing at Detroit, in the county of Wayne and State of Michigan, have invented a certain new, original and ornamental Design for a Toy Monkey, of which the following is a specification, reference being had therein to the accompanying drawing, forming part thereof.

Figure 1 is a front elevation of the toy monkey, and Fig. 2 is a side elevation of the head portion thereof.

I claim:

The ornamental design for a toy monkey, as shown.

WILLIAM F. KELLER.
